UNITED STATES PATENT OFFICE.

WILLIAM E. JACOBS, OF COLUMBUS, OHIO.

WHIFFLETREE.

SPECIFICATION forming part of Letters Patent No. 424,208, dated March 25, 1890.

Application filed January 20, 1890. Serial No. 337,470. (No model.)

To all whom it may concern:

Be it known that I, WILLIAM E. JACOBS, a citizen of the United States, residing at Columbus, in the county of Franklin and State 5 of Ohio, have invented certain new and useful Improvements in Whiffletrees; and I do hereby declare the following to be a full, clear, and exact description of the invention, such as will enable others skilled in the art to which 10 it appertains to make and use the same.

My invention consists in a whiffletree comprising a stout bar, preferably wood, and which is capable of yielding between its ends to a limited extent, a truss-rod having draft-hook and abutment eyes and serving for sustaining the said bar, said rod being securely fastened to the ends of the bar, a pulling connection in form of a bridge-loop (or plates) provided with a limitation stop-block 15 for the truss-rod to bear against when the load is being moved, the truss-rod passing behind said block, so as to be out of contact with the limitation-stop when the strain is not upon the whiffletree, and a suitable means 20 of attachment—for instance, a clevis or the like—between the whiffletree and the carriage, wagon, plow, or ditching-machine, or between the whiffletrees and evener-bars of reapers, mowers, or other agricultural implements drawn by animals.

By my invention the whiffletree can to a limited extent spring or bend into a bowed or curved form between its ends, and thus yield and relieve the shoulders of draft-animals and the harness from that sudden injurious strain experienced on starting a team to pull a heavy load, and while this is so the whiffletree during the time that the load is being moved and offering its resistance to the 35 team ceases to yield or remains comparatively rigid, and the team has direct control of the load and can move the same along steadily.

In the accompanying drawings, Figure 1 is 45 a top view of my improved whiffletree with a portion of the bridge-loop broken away. Fig. 2 is a vertical cross-section of the same. Fig. 3 is an illustration of the invention as applied to an evener device of a reaper, mower, or other agricultural implement; and Fig. 4 is a vertical cross-section of the same.

A in the drawings, Figs. 1 and 2, represents

the whiffletrees formed, preferably, of a strong elastic wood bar A', of sufficient stiffness to serve the office assigned it, and yet 55 capable of yielding and bending in a bowed or curved form between its ends, as illustrated by the dotted lines in Fig. 1, and thus act as a spring at the time when a team with a load is being started. To the end of the 60 bar A' an angular or bowed truss-rod B, having draft-hook eyes b, is fastened rigidly by means of ferrules c or other suitable means, as shown. The middle portion of this rod is coupled to the bar A' of the whiffletree A by 65 means of a strong connection in form of a bridge-loop C, which is passed around the bar A' and extended back with plate portions a proper distance, said plate portions being united some distance from their termini upon 70 a strong solid limitation stop block or piece d and bolted firmly together, as shown. The middle or bowed portion of the truss-rod lies behind the stop block or piece d between the plate portions of the bridge-loop, and in its 75 normal position stands some distance away from the same, as illustrated in full black lines in Figs. 1 and 2. Vertically through the bridge-loop connection C is provided a large hole f, and for convenience of applying the 80 whiffletree to an evener-bar E, as in Figs. 3 and 4, a smaller hole f' may be provided, one of said holes being in advance of the other. Through the large hole f a clevis-hook D is 85 passed, and through the eyes at the ends of the branches of this hook a pivot pin or bolt f² is passed for the purpose of connecting the whiffletree to a carriage, wagon, plow, or a ditching-machine or the like. When the whiffletree is attached to an evener-bar E, as 90 in Figs. 3 and 4, the clevis-hook may be substituted by a strap-loop g, having extended flat portions with holes through them, and the said loop be passed around the evener-bar E and bolted thereto, as indicated at g', 95 and a bolt g² may be passed down through the holes in the extended flat portions, and also through the small hole f' of the bridge-loop, as indicated in said Figs. 3 and 4 of the drawings. It will be seen that as there is 100 sufficient space between the truss-rod B and the stop block or piece d of the bridge-loop connection C the wooden bar A' is free to yield and bend into a curved form when the

strain of the load comes upon it at the starting of the team, and will thus continue to bend until the load has fully started, at which moment the further bending of the bar will be arrested by the truss-rod being drawn in contact with the limitation stop block or piece *d*, and thus the bar *A'* and truss-rod *B* will become so united that said rod will render the whiffletree practically stiff or unyielding, and thereupon the team will draw the load solidly and steadily without the inconvenience which results from having the whiffletree operate at all times with a spring action.

From experience with different kinds of whiffletrees it has been found that there should be a little elasticity in the same when the team starts to pull, so as not to jar the shoulders of the animals and strain the harness, but after starting the load there should be little or no spring action, so that the team shall have control or a firm hold on the load and move it along steadily.

The bridge-loop may be substituted by two plates bolted to the top and bottom of the whiffletree-bar *A'* and provided with the limitation stop block or piece *d* and the holes *f'*, as shown; but I prefer the bridge-loop, as hereinbefore described. The clevis strap-loop might also be substituted by two plates bolted to the top and bottom of the evener-bar; but I prefer the strap-loop hereinbefore described.

The whiffletree truss-rod formed with draft hooks or eyes at its ends is very useful, whether the whiffletree be made capable of yielding or not, and therefore this feature of

my invention is not confined to a spring-whiffletree.

What I claim as my invention is—

1. In a whiffletree, in combination, a yielding bar, a bridge-connection, a stop, and a truss-rod having its ends fastened to the ends of said bar and bent or bowed so as to throw its middle portion out of contact normally with the stop, the construction and combination being such that when a team starts and the load strains the whiffletree the bar is free to yield between its ends without resistance from the truss-rod and to continue to do so until the load is properly started or the middle portion of the truss-rod is brought in contact with the stop, whereupon the whiffletree, comprising bar and truss-rod, becomes substantially rigid and unyielding, substantially as described.

2. The combination, with a truss-rod *B*, having draft-hook and abutment eyes formed on it, of the yielding bar *A'*, fastened by its ends to the truss-rod, and the perforated bridge-connection having a stop against which the rod bears after the team is started, substantially as described.

3. The combination of the bridge-connection, having large clevis-holes and small pin-holes through it, with the truss-rod *B* and the yielding bar *A'*, attached by its end to the truss-rod, substantially as described.

In testimony whereof I hereunto affix my signature in presence of two witnesses.

WILLIAM E. JACOBS.
